United States Patent Office

Des. 230,216
Patented Jan. 29, 1974

230,216

HANDBAG

Clarence V. Tibbs, P.O. Box 11033,
Knoxville, Tenn. 37919

Filed Apr. 26, 1972, Ser. No. 247,916

Term of patent 14 years

Int. Cl. D3—01

U.S. Cl. D87—3 F

Fig. 1

Fig. 2

Fig. 4

Fig. 3

Fig. 5

FIG. 1 is a front elevational view of a handbag showing my new design;

FIG. 2 is a top plan view thereof;

FIG. 3 is an end elevational view;

FIG. 4 is a front elevational view thereof in open position; and

FIG. 5 is a top perspective view of the handbag in closed position.

I claim:

The ornamental design for a handbag, as shown.
